UNITED STATES PATENT OFFICE.

EDWARD S. T. KENNEDY, OF NEW YORK, N. Y.

RADIAL-TUBE STEAM-BOILER.

SPECIFICATION forming part of Letters Patent No. 375,324, dated December 20, 1887.

Application filed August 29, 1887. Serial No. 248,210. (No model.)

To all whom it may concern:

Be it known that I, EDWARD S. T. KENNEDY, a citizen of the United States, residing at New York city, in the county of New York and State 5 of New York, have invented certain new and useful Improvements in Radial-Tube Steam-Boilers; and I do hereby declare the following to be a full, clear, and exact description of the invention, such as will enable others skilled 10 in the art to which it appertains to make and use the same.

This invention relates to radial-tube or "porcupine" steam-boilers of the kind having a central cylinder or stand-pipe provided 15 with radial water and steam tubes and surrounded by a deflecting furnace and shell having deflecting-plates at different heights above the fire-box. It also embraces certain improvements on the boiler described in Letters 20 Patent granted to me September 28, 1886, No. 349,720.

The present improvements are more particularly in details of construction of the stand-pipe and its immediate attachments, whereby the 25 boiler is made much more convenient, effective, and durable in operation, and whereby hot products of combustion are more evenly and uniformly distributed around and between all the tubes of the boiler, around the entire circumference of the stand-pipe, and injurious heat-currents in any one line are avoided, and consequently the wear upon the tubes made uniform.

In making boilers of large size with stand-pipes of from twenty to forty-eight inches diameter, or more, the vertical riveted seams, necessarily used for joining the edges of the iron plate to make the cylinder, interfered with the regular spacing and setting of the radial tubes, 35 and an extra wide space was necessarily left between the tubes along the line of this vertical seam. The seam extended from bottom to top of the stand-pipe, and thus formed a direct flue-space, up which currents of flame 40 and heated products would draw with great vigor, heating the tubes on either side to excess and causing their rapid destruction, as the water was apt to be driven out of them by the detrimentally-high heat, while of course 45 the heat was drawn away from other tubes and they did not properly perform their func-

tion or do their share of service. Tubes along the seam and flue-space looked as though they had been heated red-hot and injured, while other tubes looked as if they had never been 55 heated. Uneven circulation of water and diminished steaming capacity resulted from this defective construction. In order to overcome these defects and objections, I construct the stand-pipe of short cylindrical sections and 60 rivet these sections together, so that their vertical seams shall be turned one from the other successively from left to right from one quarter to one-third or one-half the circumference of the stand-pipe, and I prefer that they shall 65 be one-quarter the circumference one from the other, so that four seams in four successive sections shall complete the circle of the stand-pipe. I do not, however, confine myself to any particular number of sections, as the number will depend upon the height of the stand-pipe. Short seams and spaces are thus made, 70 and above each space the tubes are set in close regular order, and the heat thus uniformly distributed. The hot products that 75 pass up one short flue-space come in contact with the close-set tubes above, where much of their heat is absorbed before they reach another flue-space, and the operation is repeated 80 to the top of the boiler.

My invention embraces other features of construction, which will be pointed out in the detail description, referring by letter to the drawings, and the matter constituting my invention will be defined in the claims.

In the accompanying drawings, Figure 1 represents a vertical section of my radial-tube or porcupine boiler properly set in its furnace. Fig. 2 represents a detached perspective view of the stand-pipe, with parts broken away, 90 and showing the cylindrical sections with vertical seams arranged at quarter-arcs one from the other. Fig. 3 represents an enlarged detail view of the base of furnace and stand-pipe.

The furnace and shell A of the boiler are 95 built of brick and lined a sufficient height with fire-brick mounted upon a foundation, W. The shell is provided with numerous sight-openings and doors u, and is surmounted by a suitable hood and smoke-stack. A fire-chamber, C, and an ash-pit, D, are provided 100 in the lower part of the furnace-walls, and

the fire-chamber is provided near its top with brick-deflector *c*, as shown. Iron deflecting plates *c'* project inward at different heights from the walls above.

5 The stand-pipe *B* is composed of cylindrical sections 1 2 3 4, &c., as shown. It is provided with a flanged and dished lower head, *I*, riveted to the cylindrical portion, and the walls of the cylinder extend down and rest upon the 10 circular cast-iron foundation-plate *i*, which is located upon the supplementary brick foundation *n*, composed of one course of brick, which prevents water in the ash-pit from coming in contact with the iron of boiler. The 15 inclined brick *o* protects the iron sill of the door-frame and makes removal of ashes more convenient. The usual fire and ash doors, *a* and *a'*, are provided.

By reference to Fig. 2 the short cylindrical 20 sections 1 2 3 4 5 of the stand-pipe may be seen, with their vertical riveted seams *N'*, *N²*, *N³*, *N⁴*, and *N⁵* arranged at quarter-arcs of the circumference of the cylinders one from the other successively from left to right. As shown by 25 the holes, the tubes are inserted in close order, with regular spaces above and below, so that the fine-spaces made by the tubes on each side of the seams extend but a short distance, and that hot products are therefore well distributed around the entire circumference of the stand-pipe and in contact with all the tubes. The stand-pipe has secured in it the wrought-metal tubes *b*, having the metal at their outer ends closed and welded upon itself, so as to 30 form a seamless hemispherical end of thickened metal possessing great strength and durability. These tubes are protected by a 35 separate Patent granted to me August 23, 1887, No. 368,836. The stand-pipe at top is provided with a peculiar arrangement of steam-drying tubes and steam-discharge pipe, 40 claimed in another Patent, No. 310,891, January 20, 1885. The lower end of the stand-pipe forms a mud-drum, *L*, (see Fig. 3,) which receives the sediment from the currents of 45 circulating water above, and is provided with a man-hole, *K*, and properly-secured plate *K'*, having handle *l*. This man-hole affords access to the stand-pipe for expanding the tubes 50 in their holes and afterward for inspecting the tubes and cleaning them and the stand-pipe and removing deposits from the mud-drum. The feed-pipe *w* connects with the stand-pipe just below the grate, and extends 55 out through the brick wall of the furnace. The blow-off pipe *y* passes into the stand-pipe just below the grate, and its inner end is bent down to near the bottom of the mud-drum. At a suitable height above the floor of the 60 ash-pit a ledge, *d*, is formed in the brick furnace-wall and covered by a cast-iron plate, and at the same height the stand-pipe has riveted to it the wrought-iron brackets *h*, which support the wrought-iron ring *H*. This 65 ring is sufficiently large to set out from the

stand-pipe and leave a clear annular space between the two, as shown in the drawings, for circulation of air, whereby burning and injury of the stand-pipe by excessive heat at this point is prevented. The ledge and ring 70 support the outer and inner ends, *e* *e'*, of grate-bars *E*. The grate-surface is circular in form, and in large boilers extends entirely around the stand-pipe. The water-column pipe *x* connects below the grate with stand-pipe, and at the junction of the horizontal and vertical portion is connected a three-way valve, *t*, from which leads a discharge-pipe, *x'*, into the ash-pit. 75

Having described my invention, what I 80 claim, and desire to secure by Letters Patent, is—

1. In a radial-tube boiler, the stand-pipe composed of cylindrical sections having their vertical riveted seams in adjacent sections 85 placed at lateral intervals one from the other amounting to from one-fourth to one-half of the circumference of the cylinders, as and for the purpose described.

2. In a radial-tube boiler, the stand-pipe 90 composed of short cylindrical sections riveted together in such manner that the vertical riveted seams of adjacent sections shall extend in different vertical lines at suitable distances apart, whereby the radial tubes may be arranged and spaced in the successive sections, 95 so as to divert and distribute the heated currents around the stand-pipe.

3. In a radial-tube boiler, the stand-pipe 100 composed of short cylindrical sections connected together, and the vertical seams of adjacent sections placed at quarter-arcs of the circumference distant one from the another, as and for the purpose described.

4. In combination with a stand-pipe resting upon the floor of the ash-pit, the brackets *h*, riveted thereto, and ring *H*, of larger diameter 105 than the stand-pipe, so as to provide an annular space between the two, and resting on the brackets for supporting the inner ends of 110 the grate-bars.

5. In combination with a radial-tube boiler, the furnace-walls having a ledge, *d*, at the 115 top of the ash-pit, the brackets *h*, riveted to the stand-pipe, and ring *H*, of larger diameter than the stand-pipe, resting on the brackets for supporting the circular grate.

6. In combination with a radial-tube boiler, the central supplementary brick foundation rising above the floor of the ash-pit, and foundation-plate *i*, for supporting the lower end of the stand-pipe above the floor of the ash-pit and preventing injury thereof by water on the ash-pit floor.

In testimony whereof I affix my signature in 125 presence of two witnesses.

EDWARD S. T. KENNEDY.
